UNITED STATES PATENT OFFICE.

CHARLES ALBERT BALL, OF MARION, INDIANA.

COMPUTING BALLOT-BOX.

No. 902,365.

Specification of Letters Patent. Patented Oct. 27, 1908.

Application filed September 23, 1907. Serial No. 394,104.

To all whom it may concern:

Be it known that I, CHARLES ALBERT BALL, a citizen of the United States, and a resident of Marion, in the county of Grant and State 5 of Indiana, have invented a new and useful Improvement in Computing Ballot-Boxes, of which the following is a full, clear, and exact description.

The purpose of the invention is to provide 10 a computing ballot box or voting machine, adapted for the use of fraternal and benevolent societies, lodges, clubs and the like, whereby a more reliable and secretive method of conducting the election of applicants for 15 membership is obtainable than at present, and to provide a method of conducting a secret affirmative or negative ballot without the aid of tellers or the use of paper ballots.

Another purpose of the invention is to 20 provide a mechanical device that admits of any number of votes being cast as a ballot, and which will unerringly disclose the number of votes cast *pro* and *con*, and further, to so construct the ballot box that the total 25 of the votes will remain concealed until properly disclosed, and wherein only one white and one black ball is visible to each voter, thus preventing speculation as to the number and character of the votes cast, and 30 wherein further only one black or white ball can be moved by a voter, a signal being given at the casting of the vote.

It is also a purpose of the invention to 35 construct a device of the character described in a very simple, durable, economic manner, and so that its use may be readily comprehended by any person of ordinary intelligence.

The invention consists in the novel construction and combination of the several 40 parts, as will be hereinafter fully set forth and pointed out in the claims.

Reference is to be had to the accompanying drawings forming a part of this specification, in which similar characters of reference indicate corresponding parts in all 45 the figures.

Figure 1 is a plan view of the device; Fig. 2 is a longitudinal section taken practically on the line 2—2 of Fig. 1; Fig. 3 is 50 a plan view of a portion of the device, the protecting screen or cage and the cover

therefor being removed; Fig. 4 is a plan view of the device, the cover and the partitions beneath it being broken away, and Fig. 55 5 is a bottom plan view of the devices, parts of the partitions being also broken away.

The ballot box A is preferably given the conventional shape, namely it is ordinarily constructed in a rectangular form, and may 60 be made of any suitable material, and is provided with a handle a located usually at one of its ends. At or about the central portion of the cover 10 of the box parallel elongated openings 12 and 13 are located, as is best 65 shown in Figs. 1 and 3. These openings are beneath a cage 14 that is preferably made of a perforated or reticulated material, and is open at one end to permit the introduction 70 of the fingers of the hand to reach the openings 12 and 13, and a slide-way 15 extends along the sides of the cage and at the closed end thereof, and a box cover 16 has movement in the said slide-way, being provided with a drop door 17 so that when the ballot 75 box is not in use the cover 16 may be slid over the cage and its hinged portion 17 dropped down so as to protect the interior of the box. The box is divided into compartments by means of an upper horizontal partition 18 and an intermediate partition 19, which latter partition is removed a predetermined distance from the bottom 20 of the box body of the device, and at one end of 80 the box body, that end preferably where the handle a is located, two sliding doors 21 are produced, one at each side of the center, said doors being shown in Figs. 2 and 5, and these doors 21 when they are closed constitute a portion of the bottom of the box body as is 85 shown in Fig. 5.

In the arrangement of the ballot box, two groups of mechanism are employed, one identical in construction with the other, and these two mechanisms are located one at 95 each side of the center of the box body, extending longitudinally thereof. One mechanism is below the opening 13 and the other below the opening 12, and at the opening 13 a black ball 22 is visible, although any desired number may be employed, and at the opening 12 a single white ball 23 appears. As the two groups of mechanism are identical in construction, I will describe only the 100

mechanism that is operated by the movement of the black balls. The order above stated may, however, be reversed.

Below the opening 13 an inclosure 24 is constructed, preferably of oval form, as is shown in Fig. 4, and this inclosure extends from the partition 18 to the top 10 of the device. At one end portion of the inclosure 24, a shaft 25 is mounted to turn in the top 10, the partitions 18 and 19, and the bottom 20, but at the other end of the inclosure which is nearest the handle *a*, a second shaft is mounted to turn in the top 10, and the partition 18 only, which latter shaft is designated as 26. A star wheel 27 is secured on the shaft 25 between the partition 18 and the top 10, and a like wheel 28 is similarly located on the opposing shaft 26 as is shown in Figs. 2 and 4, and these wheels are preferably provided with five points, but the number of points may be changed as desired. These star wheels 27 and 28 are practically turn-stiles, since they receive between their points the balls 22 or 23, and by the movement of the exposed ball in direction of the arrow shown in Fig. 3, the said turn-stiles 27 and 28 are given movement. Each of the star wheels or turn-stiles 27 and 28 is provided with an attached disk 29 at its lower end, but of much greater diameter, and these disks form supports for the balls 22 or 23, and the balls are guided between the shafts 25 and 26 by means of guide plates 30, that extend from one shaft to the other at each side, as is best shown in Fig. 4. The handle-end *a* of the device will be farthest away from the voter, and the balls as voted are moved toward the voter. The white and black balls start in the same direction, but move in reverse elongated circles back to the starting point.

At the lower end portion of the shaft 25 a sprocket pulley 31 is located, and on the corresponding shaft of the opposing mechanism a similar pulley 32 is secured, one pulley being at a greater elevation from the bottom 20 than the other, as is shown in Fig. 2. At a point in a line between the opposing shafts 25 and 26, another shaft 33 is secured between the bottom 20 and the partition 19, and on this shaft 33 two wheels 34 and 35 are mounted to turn, or these wheels may be secured to the shaft and the shaft be made to rotate in suitable bearings. Each wheel 34 and 35 is provided with five points or teeth 36 at equal distances apart, and as the wheels 34 and 35 rotate, the teeth 36 are brought in engagement with a tongue 37 having a suitable support 38, and as the said tongue is engaged by a tooth and then released, it will sound an alarm or give a signal; the tongue may be substituted by a pawl if so desired.

A crossed belt 38^a is carried around the sprocket pulley 32 and around the upper 65 toothed wheel 34, and a straight belt 39 is carried around the sprocket pulley 31 and the lower toothed wheel 35, as is best illustrated in Fig. 5. Thus it will be observed that no matter whether a black or a white ball is 70 moved, the star wheel 27 belonging to the mechanism supporting the ball moved will be rotated, and by reason of the use of a straight belt and a crossed belt, the points or teeth on the wheels 34 and 35 will agitate the tongue or pawl, as the case may be, from the same direction, thus insuring the same sound from the use or movement of either a white or a black ball. In order that two balls, a black and a white one, shall 80 not be moved at the same time, and to render it positive that only one ball can be moved respecting one vote, toothed wheels 40 are secured at the lower ends of the shafts 25, and the teeth of the said wheels 85 are adapted to be engaged by a double pawl 41, which is pivoted about centrally between two arms 42 at a point between the aforesaid wheels 40, as is shown in Fig. 5, and the arms of this pawl are provided 90 with teeth 42^a, adapted to mesh with the teeth of the wheels 40, but both arms are not normally in engagement with the two wheels, one arm being always out of engagement with a wheel 40, as is shown in 95 Fig. 5, so that if a white ball is pushed forward to be counted as a vote, the arm of the pawl belonging to the mechanism set in motion would slip from the wheel 40 and would consequently lock the corresponding 100 wheel of the other mechanism, and should an attempt be made to push both balls at the same time, the pawl 41 would act to lock both of the wheels 40.

Each shaft 25 is provided with a disk 43 105 fast thereto and located in the compartment between the partitions 18 and 19. This disk 43 is provided with five groups of teeth, designated as 44, or a number of groups of teeth corresponding to the number of points 110 in the turn-stiles or star wheels employed. Ordinarily there are three teeth in a group, as illustrated, but I do not confine myself to any specific number, and the groups of teeth are at regular distances apart. The 115 teeth of the disk 43, as the said disk revolves, engage with the teeth of a pinion 48, that is secured to or is an integral portion of a disk 46, which is a units disk, and this units disk and its accompanying gear 47 120 are mounted to turn on a shaft 48 journaled in bearings in the partitions 18 and 19, as is shown in Fig. 2. This units disk 46 is provided with a single group of teeth 47 at its periphery, and the said teeth are usually 125 four in number, as is illustrated in Fig. 4.

and when this units disk has made one revolution, its teeth 47 engage with the teeth of a tens disk 49, that is mounted to turn on a shaft 50, likewise journaled in the partitions 18 and 19, and on this tens disk 49 a smaller disk 51 is secured, and the smaller disk 51 is also provided with a single group of teeth 51^a at its periphery, and this group of teeth is usually four in number also, and 5 after the tens disk has made one revolution, its teeth 51^a are brought in engagement with the teeth of a gear 53 having an attached disk 54, which is a hundreds disk, and the gear 53 and accompanying disk 54 are 10 mounted to turn on a shaft 52, that is likewise journaled in the partitions 18 and 19, as is indicated in Figs. 2 and 4, but the disk 54 is below the partition 19 and its under face, bearing the numerals, is within a cap 15 54^a, shown in Fig. 5.

The units disk 46 is provided with numerals at its bottom, adjacent the periphery, reading from 1 to 9, including 0, and the tens disk 49 is similarly numbered, and ordinarily the disk 54 designating hundreds is provided with numerals on its outer face, reading 1, 2, 3, 4, 0, or as high as may be desired. Both the units disk and the tens disk are provided with recesses 55 in their under 20 faces, and in each of said recesses a pawl 56 is pivoted, and the said pawls are adapted to engage with ratchet teeth 57 produced in circular depressions in the upper face of the partition 19, so that the said units and 25 tens disks can be turned in one direction only, and the hundreds disk should have similar rotation. When the disks are to be turned so as to bring the zeros in registry, as is required at the commencement of a ballot, they are given individual movements by 30 means of handles 58 attached to their respective shafts, which handles are reached whenever the bottom doors 21 are opened. In the partition 19 two openings are produced, designated respectively as 59 and 60, and the numerals on the units disk are visible at the opening 59, and those on the tens disk at the opening 60, while the numerals 35 on the hundreds disk are visible at an opening 61, as is shown in Fig. 5; thus it will be observed when the units disk makes one complete revolution it causes the tens disk to move one point, and when the tens disk has made a complete revolution it causes the 40 hundreds disk to move, and in this manner an accurate accounting is assured.

The gear 53 is provided with a detent 62, which detent is located at the upper side of the wheel and engages with a ratchet surface 63 on the under face of the partition 18, as is shown in dotted lines in Fig. 2.

From present information there is apparently no ballot box in use sufficiently secret-

ive to carry out the intent and purpose for which a secret ballot is desired. A ballot box, that gives the first voter the full number of balls or cubes to draw from cannot be fair for the succeeding voters, for the reason that the balls or cubes are drawn from a lot diminishing in number with each ballot cast, so that after a number of balls or cubes have been cast, a practiced eye can detect from the balls or cubes uncast, the complexion of the vote and determine how a predecessor has voted; also in the present ballot box, a ballot which is being deposited in the box can frequently be seen by persons other than the voter. Again, after a ballot has been completed, it is often more or less difficult to make a correct reading of the result, for the reason that the balls or cubes are deposited in a receptacle that frequently admits but a little light, rendering it possible to make a miscount. My ballot box is designed to overcome the above-mentioned and other 85 defects, since it admits of any number of votes being cast, and provides for an absolutely secret accounting of the votes, and since there is but one black ball and one white ball visible at a time, there will be no 90 uncast votes to speculate upon. Further, it is not necessary to pick up a ball and risk exposing it, and a blind or near-sighted person is able to vote without assistance. Finally, but one vote can be cast at a time, 95 and the sum of the votes *pro* and *con* can be accurately ascertained at a glance upon opening the doors at the bottom of the box.

It will be understood that the major portion of one ball, and probably a portion of 100 the following ball, is visible at each opening 12 and 13, and that when the practically fully exposed ball 22 or 23 is pressed forward with the fingers of the operator, the partially exposed ball will take the place of 105 that pushed forward, and the registering mechanism will have been operated to register one vote, black or white.

Having thus described my invention, I claim as new and desire to secure by Letter Patent,—

1. A voting machine comprising a casing, a plurality of registers in the casing, a series of register actuating ballots for each register, means, whereby the ballots of each series are successively and repeatedly brought into position to be operated, one at a time, and means for preventing the ballots of all the series from being simultaneously operated.

2. A voting machine comprising a casing, 120 a plurality of registers therein, a plurality of series of register actuating ballots, one ballot for each series, being at all times visible, and means for confining and guiding each of said series within the machine 125 casing to cause each ballot of the series when

moved to repeatedly move past and operate its register.

3. A voting machine comprising a casing, a plurality of registers therein, a plurality

5 of series of register actuating ballots, one series for each register, means for confining and guiding each of said series within the

machine casing to cause each ballot of the series when moved to repeatedly move past

10 and operate its register, means for exposing the reading faces of the individual registering mechanisms, an alarm, and means for operating the alarm as each register actuating ballot is progressively moved.

15 4. A ballot box having an opening therein and a series of balls mounted for sliding and rolling movement below said opening, a single ball of one of the series appearing at said opening.

20 5. A ballot box having an opening therein and a series of balls mounted for sliding and rolling movement below said opening, a single ball of one of the series appearing at said opening, and an adding mechanism 25 brought into action by the movement of the balls.

6. In a ballot box, the combination with a box having an opening therein, a series of balls mounted for movement beneath said 30 opening, only one ball being visible at said opening, and guides for the said balls, of an adding mechanism located within the box, a driving mechanism operated by the balls in their movements, and connections 35 between the driving mechanism and the adding mechanism.

7. A ballot box provided with openings in its top, side by side, a series of balls 40 mounted to travel below each opening, one series of balls being black and the other white, and a single ball only of each series appearing at the opening provided for the said series, an adding mechanism for each series of balls, and means for independently 45 setting the respective mechanisms in motion by the movement of the balls pertaining thereto.

8. A ballot box provided with openings in its top, side by side, a series of balls 50 mounted to travel below each opening, one series of balls being black and the other white, and a single ball only of each series appearing at the opening provided for the said series, an adding mechanism for each 55 series of balls, means for independently setting the respective mechanisms in motion by the movements of the balls pertaining thereto, an alarm device also operated by the movements of the balls, and guides for the 60 said balls.

9. A ballot box provided with openings in its top, side by side, a series of balls mounted to travel below each opening, one series of

balls being black and the other white, and a single ball only of each series appearing at the opening provided for the said series, an adding mechanism for each series of balls, means for independently setting the respective mechanisms in motion by the movements of the balls pertaining thereto, an alarm device also operated by the movements of the balls, guides for the said balls, a cage located over the said openings, and a detent mechanism arranged to prevent the simultaneous movement of the two exposed balls. 75

10. In a voting machine, a carrier for the ballots, consisting of opposing star wheels, disks secured to the said wheels, extending beyond the periphery thereof, adapted to support the ballots, and rotary supports for 80 the star wheels, said wheels being simultaneously turned by the movements of the ballots on said supporting disks.

11. In a voting machine, a carrier for the ballots, consisting of opposing star wheels, 85 balls adapted to be received between the points of the star wheels, supporting disks for the ballots, carried by the star wheels, independent rotary supports for the star 90 wheels and ballots, the wheels being simultaneously revolved by the movement of the ballots.

12. In a voting machine, a body provided with openings therein, movable ballots within the body, exposed singly at said openings, and a cage located over said openings. 95

13. A voting machine comprising a casing having an opening therein, a register in the casing, a plurality of register actuating ballots, and means, whereby the ballots are successively and repeatedly presented one at a time, at the opening. 100

14. In a voting machine, a casing having an opening therein, a register in the casing, a 105 plurality of register actuating ballots, and means for supporting and guiding the ballots so as to bring them successively opposite the opening of the casing to permit the exposed ballot to be moved to operate the 110 register.

15. In a voting machine, a casing having an opening therein, a register in the casing, a plurality of register actuating ballots arranged in the casing below the opening 115 thereof so that but one ballot will be exposed at said opening, and means, whereby when the exposed ballot is moved, the register will be operated and the ballots caused to travel in a circuit. 120

16. A voting machine comprising a casing having openings therein, a plurality of registers in the casing, a plurality of series of register actuating ballots, one ballot for each series being at all times visible at an opening of the casing, means for supporting and 125

guiding each of said series of ballots to permit each ballot of the series to be repeatedly moved to operate its register, and means for preventing both registers from being simultaneously operated.

17. A voting machine comprising a casing, a plurality of registers in the casing, a plurality of register actuating ballots for each register, means whereby the ballots of each series are brought into position to be oper-

ated, one at a time, an alarm, and means whereby the alarm will be sounded when the ballots of either series are operated.

In testimony whereof I have signed my name to this specification in the presence of 15 two subscribing witnesses.

CHARLES ALBERT BALL.
